Primary Examiner — Lakiya G Rogers*Assistant Examiner* — Carissa C Fitts*(74) Attorney, Agent, or Firm* — Paul D. Bianco; Fleit Gibbons Gutman Bongini & Bianco PL(57) **CLAIM**

The ornamental design for a lamp, as shown and described.

DESCRIPTION

FIG. 1 is a perspective view of a lamp according to the present invention;

FIG. 2 is a first side view of the lamp of FIG. 1;

FIG. 3 is a front view of the lamp of FIG. 1;

FIG. 4 is a second side view of the lamp of FIG. 1;

FIG. 5 is a back view of the lamp of FIG. 1;

FIG. 6 is a top view of the lamp of FIG. 1; and,

FIG. 7 is a bottom view of the lamp of FIG. 1.

The broken lines show unclaimed portions of the lamp and form no part of the claimed design.

1 Claim, 6 Drawing Sheets(56)
